NECKTIE

Carl O. Swanson, Minneapolis, Minn.

Application March 30, 1938, Serial No. 198,840

5 Claims. (Cl. 2—154)

This invention relates to improvements in neckties and supporting means therefor.

In neckties of the ready tied kind, some provision is necessary for properly holding the tie on the shirt collar of the wearer and probably the most popular method is the use of an elastic band which is placed around the collar and hooked together at its ends. This device, however, has the disadvantage that the shirt collar is wrinkled by its use, due mainly to the tension of the band which is necessary to hold the tie properly on the collar. As a result the collar is not only uncomfortable but is very unsightly. A second device uses an apertured tab or retainer of some sort which is attached to the tie and adapted to be fitted over the collar button in order to retain the tie in place. This device, of course, will not wrinkle the collar band but it is extremely difficult to use and to button in place as will be readily understood.

Having in mind the foregoing defects of the prior devices, the primary object of this invention is to provide a mounting, fastening, or supporting means which may be readily assembled on the necktie and conveniently engaged with the collar to retain the tie in place without in any way wrinkling the collar or applying an uncomfortable tension around the collar. Another object is to provide a bow tie mounting or supporting means wherein the connection is made to the frontal flaps or wings of the collar, thus permitting the collar to be buttoned before the tie is put in place and freeing the tie of any connection to, or around, the neck band of the collar. A further object is to provide a device of this kind in a simple, durable and inexpensive form.

The foregoing and other objects, together with means whereby the same may be carried into effect, will best be understood from the following detailed specification, reference being had to the accompanying drawing wherein:

Fig. 1 is a frontal view of a bow tie as arranged on a collar and supported by the device of my invention.

Fig. 2 is a horizontal section through the collar along the line 2—2 in Fig. 1 and showing the bow tie in place.

Fig. 3 is an enlarged perspective view showing the fastening device of Figures 1 and 2 and also showing adjacent parts of the bow tie.

Fig. 4 is a rear elevation of a bow tie showing a modified form of fastening device.

Fig. 5 is a plan view of the device of Fig. 4 and showing in section the adjacent portions of the collar.

Fig. 6 is a rear elevation of still another modified form of fastening device.

Fig. 7 is a plan view of the device of Fig. 6 and showing in section the adjacent portions of the collar and also a portion of the tie.

In carrying out my invention as embodied in the device shown in Figures 1, 2 and 3, I provide a fastening assembly or device designated generally at 10 and which is applied, for example, to a bow tie A made up of the medial knot B 10 and the flaring and laterally extending portions or wings C in the conventional manner. My device comprises a rigid main or base member or mounting bar 11 which is placed at the rear side of the tie and is held thereon by sewing it to the knot B as indicated at 12. The bar 11 then extends endwise or horizontally of the tie A and projects outwardly at its ends behind the wings C. The bar is, of course, provided with apertures 13 for sewing it in place on the tie.

The outer end portions of the bar 11 support fastening members or clasps designated at 14 and which are pivotally mounted between hinge ears 15 turned rearwardly from the lateral margins of the bar and apertured to pass transversely extended hinge pins 16. The margins of the clasp members 14 have similarly turned and apertured ears 17 located intermediate their ends and which pivotally engage the hinge pin 16 to thereby support the members at the rear of the bar 11. The outer extremities of both the bar 11 and the clasp members 14 are oppositely turned to provide interfitting clasp jaws designated generally at 18 and the margins of which may be serrated or toothed as shown in order to facilitate their gripping action. Torsional coil springs 19 are coiled around the hinge pins 16 and have their opposite ends 20 braced against the bar 11 and inner ends of the clasp members 14 to thereby tend to normally close the gripping jaws 18.

The bow tie thus arranged is adapted to be worn on the collar D which comprises the neck band E buttoned at the front at F and the frontal flaps or wings G spaced apart at the frontal side of the collar in the usual manner. In use, then, the collar is buttoned around the neck and the clasp members 14 are pressed between the fingers at their inner ends to thus swing the jaws 18 apart. The tie, with the jaws thus opened, is then placed between the collar flaps G at the proper point and is so located and manipulated that the inner margins of the flaps G will enter between the clasp jaws. The clasp members are now released and the springs 19 cause the jaws to close so that their serrated extremities en-

gage and tightly grip the collar flaps G as shown in Fig. 2. The tie is thus held in place upon the collar but, since it has no connection or band encircling the neck band, the collar cannot be 5 wrinkled or uncomfortably constricted around the wearer's neck.

In lieu of the construction just described, I 10 may employ slightly different collar engaging elements as shown in Figures 4 and 5. Here the bar 11^a is sewed at 12^a to the tie knot B but the ends 18^a are apertured at 21 to slidably receive the fastening members 14^a which now take the form of substantially U-shaped wire yokes with their legs 22 slidably mounted through the 15 said apertures and with the extremities of the said legs turned outwardly. The bights 23 of these yokes are joined by a retractile coil spring 24 which extends medially along the rear face of the bar 11^a and acts to normally draw the yokes inwardly toward each other. The outer extremities of the legs 22 are provided with sharpened hooks 25 turned rearwardly and inwardly.

In the use of this type of fastener, the members 14^a are pulled outwardly or spread apart somewhat, and in this condition have their hooks 25 pierced through the collar flaps G as shown in Figure 5. Then the members are released and the spring 24 contracts to place a slight tension on the hooks 25 which is sufficient to hold them in 20 engagement with the flaps G and thus retain the tie in place on the collar.

In Figures 6 and 7 still another embodiment of my invention is shown and here the bar 11^b is extended some distance outwardly behind the 35 tie wings C so that its outer ends serve as clasp jaws as will appear. Another bar 11^c is connected or bears against the bar 11^b medially, as indicated at 26 and extends outwardly behind the same. These two bars 11^b and 11^c are made up 40 from spring material and their free outer ends 18^b and 18^c are adapted to normally stand flatly together. The extremities 27 are, however, flared apart to facilitate the entrance of the collar flaps G therebetween.

45 In use, this device is fastened and supported by the collar flaps by inserting the flaps between the ends 18^b and 18^c which then exert a gripping or clasping action thereon as will be understood.

50 It will be noted that the two bars 11^b and 11^c are enclosed within the knot B which is readily accomplished by winding the material forming the knot around the said bars or by inserting the bars endwise through the knot. These bars may also 55 be sewed to the tie if so desired.

In order that the tie may have the appearance of fitting closely to the collar, the wings C may be formed to partially enfold the clasp elements 14 as shown. This will be facilitated somewhat by the 60 enclosure of the medial portions of the bars 11—11^a etc. in the tie knots A and it is contemplated that this arrangement may be used if desired or found necessary.

The fastening devices as herein disclosed are not limited to use upon bow ties but may be used, if desired, to attach ready tied four-in-hand ties or cravats to the collar. In this case the supporting members or clasp members may be exposed to view but may be made of ornamental appearance so that this is no objection. 5

While I have herein set forth certain preferred embodiments of my invention, it is understood that I may vary therefrom in minor details, not departing from the spirit of the invention and within the scope of the appended claims. 10

Having thus fully disclosed my invention, what I claim as new and desire to secure by Letters Patent is:

1. In combination with a ready tied necktie, means for supporting the necktie upon the flaps of a collar, the same comprising a rigid mounting member secured to the rear of the necktie, and hooked members slidably mounted on the mounting member and effective to releasably engage the collar flaps and support the necktie thereon. 15

2. In combination with a ready tied necktie, means for supporting the necktie upon the laterally spaced flaps of a collar, the same comprising a rigid mounting member secured to the rear of the necktie, yoke members slidably mounted on the mounting member and laterally extended therefrom, hooks formed at the outer ends of the yoke members and adapted to engage the collar 30 flaps, and a spring stretched between the yokes to normally draw the same inwardly toward each other. 25

3. In combination with a necktie, means for supporting the same upon the laterally spaced flaps of a collar, comprising members slidably mounted in laterally spaced positions on the necktie and having hooks at their outer ends for engaging the collar flaps, and spring means normally drawing the members together for retaining 40 the hooks in engagement with the collar. 35

4. A device for supporting a necktie upon the laterally spaced flaps of a collar, comprising a bar member sewed to the rear of the tie and having apertures in its laterally disposed ends, 45 U-shaped members slidably mounted by their legs through the said apertures, hooks formed at the laterally turned extremities of the legs for engaging the collar flaps, and a retractile coil spring stretched between the U-shaped members for normally drawing the same inwardly and retaining the hooks in engagement with the collar. 50

5. In combination with a ready tied necktie, means for supporting the necktie upon a collar 55 comprising slidably supported and yieldably connected hook members mounted on the tie and extending toward opposite sides thereof for engagement with spaced ends of the collar to support the tie thereon. 60
